METHOD AND MEANS FOR TRUING CHASER BARS

Filed Jan. 10, 1921

FIG. 2.

FIG. 3.

INVENTOR

Conrad Jobst,
By *Conrad Crompton*,
His atty.

UNITED STATES PATENT OFFICE.

CONRAD JOBST, OF TOLEDO, OHIO, ASSIGNOR TO ROBERT L. ELLERY, OF TOLEDO, OHIO.

METHOD AND MEANS FOR TRUING CHASER BARS.

Application filed January 10, 1921. Serial No. 436,080.

To all whom it may concern:

Be it known that I, CONRAD JOBST, a citizen of the United States, and a resident of Toledo, county of Lucas, and State of Ohio,

5 have made an Invention Appertaining to Methods and Means for Truing Chaser Bars; and I do hereby declare the following to be a full, clear, and exact description of the invention, such as will enable others 10 skilled in the art to which it appertains to make and use the same, reference being had to the accompanying drawings, and to the characters of reference marked thereon, which form a part of this specification.

15 This invention relates to truing means for thread cutting chasers for use particularly when accurate work is desired.

It is found in practice, in the manufacture of chasers for thread cutting purposes, 20 that upon hardening a chaser, after cutting threads thereon, a certain amount of distortion or warping of the chaser always takes place so that it is necessary to true the chaser before cutting a thread therewith to 25 prevent error in the cut thread.

The object of my invention is the provision of a simple method and means for truing chasers preparatory to using the same, whereby a true and accurate thread 30 may be cut thereby.

The invention is fully described in the following specification, and while, in its broader aspect, it is capable of embodiment in numerous forms, a preferred embodiment 35 thereof is illustrated in the accompanying drawings, in which,—

Figure 1 is a side elevation of an apparatus embodying the invention with parts thereof broken away and with a set of chasers mounted in truing position thereon. Fig. 2 is a top plan view of the chaser holder of the apparatus with chasers held in truing 40 position thereby, and Fig. 3 is an enlarged sectional detail of the interengaging threads 45 of a chaser and gauge.

Referring to the drawings, 1 designates a chaser holder adapted to be mounted on a movable table 2 and fixed thereto in any suitable manner, as for instance, by magnetism. This holder has a centrally disposed vertical socket 3 for receiving the stem 4 of a master thread gauge stud 5 rising above the holder. The gauge 5 has its periphery provided with a master thread 50 and is preferably longitudinally notched or cut away at intervals therearound to provide

a number of longitudinally extending threaded ribs or projections 6 corresponding to the number of chasers to be trued, four being shown in the present instance. 60

A plurality of standards 7, four in the present instance, rise from the holder base in equidistantly spaced circular order around the thread gauge 5, and each has a chaser clamping face offset in the same direction, circularly of the gauge, from respective radii thereof, so that such face is tangential to a circle struck around the gauge axis. A clamping member 8 is secured to the clamping face of each standard 7 by a 70 screw 9, or in any other suitable manner, and cooperates with the standard to clamp a chaser 10 thereto with the longitudinal line of the chaser in register with a radius line of the gauge axis, as shown by the line 75 *a* in Fig. 2, and with its cutting nose in engagement with the gauge thread.

In practicing the invention, each chaser 10 of a set, after being tempered, is placed between a respective standard 7 and clamp 8 80 with the edge thereof to be trued projecting above the top plane of the standard and of the gauge 5. The chaser is then pushed inward against the gauge 5 with its thread fitting perfectly with the gauge thread, and 85 is then clamped rigidly in such position to the standard by a tightening of the screw 9. This having been done with all the chasers of a set, the holder is clamped to a table 2 by magnetism, or in any other suitable manner, and moved backward and forward by a movement of the table under a wheel or other grinding medium 11 by which the exposed upwardly projecting edges of the chasers are ground to true form. The trued 90 surfaces of the chasers are the surfaces which are intended to bear against the trued chaser coacting surfaces of a die carrying head. 95

It is preferable to reduce the point of engagement of a chaser with the gauge 100 thread as much as possible so that the chaser may be more easily and accurately squared therewith, and for this reason the threaded end of each chaser is intended to lap only a restricted edge portion of a 105 threaded rib 6 of the gauge 5 so that only the point or end edge of one is in engagement with the point or side edge of the other.

To further facilitate a perfect and accurate matching of the gauge and chaser 110 threads when one is placed in contact with

the other, the thread groove in the gauge 5 is slightly enlarged at opposite sides of its pitch line as shown at 12 in Fig. 3, so that the chaser threads will only have contact 5 with the gauge threads at the pitch line thereof, thus preventing any small amount of dirt or minute particles, which may have collected in the base portion of a base thread groove, or along the outer side walls there- 10 of, from coacting with the chaser thread to prevent a true and accurate inter-fitting of one with the other.

I wish it understood that my invention is not limited to any specific construction, ar- 15 rangement, or form of the parts, or to any specific method of practicing the same, ex- except in so far as such limitations are speci- fied in the claims.

Having thus described my invention, 20 what I claim as new, and desire to secure by Letters Patent,—

1. The method of truing a thread cutting chaser bar, which consists in placing the threaded end of a chaser in true inter- 25 fitting engagement with the thread of a gauge part, then securing the bar in rigid relation to the gauge part, and then acting on an exposed part of the chaser bar to true the same.

30 2. A device of the class described, comprising a holder, a master thread gauge fixed to the holder, and means for clamping a thread cutting chaser bar to the holder with its threaded end in true engagement 35 with the gauge thread and with a surface disposed in position to be trued.

3. In a device of the class described, a holder having a plurality of standards ar- ranged around a central point, a threaded gauge stud fixed to the holder in central 40 relation to the standards, and means for clamping a chaser bar to each standard with the threaded end of the bar in true interfitting engagement with the gauge stud thread and with a surface thereof in 45 position to be trued.

4. In an apparatus of the class described, a holder having a threaded gauge stud rising therefrom, and means carried by the holder at spaced intervals around the stud 50 for holding a plurality of chaser bars in rigid relation to the stud with their threaded ends in true interfitting engagement with the stud thread.

5. In a device of the class described, a 55 stud having a threaded gauge rib extending longitudinally thereof, and means for rigidly holding a chaser bar with its threaded end in true interfitting engagement with the gauge thread, and only slightly over- 60 lapping the rib edge.

6. In a device of the class described, a member having a gauge thread with the thread groove enlarged at opposite sides of the pitch line whereby the thread of a 65 work-piece placed in engagement with the gauge thread will have coaction only with the pitch portion of the gauge thread helix.

In testimony whereof I have hereunto signed my name to this specification.

CONRAD JOBST.
